PHASING AND DRIVE-COUPING ARRANGE-
MENT FOR FACSIMILE MACHINESJohn R. Shonnard, New York, N. Y., assignor to
Times Facsimile Corporation, a corporation of
New York

Application December 31, 1943, Serial No. 516,341

8 Claims. (Cl. 178—69.5)

1

This invention relates to telegraph machines and more especially to driving and phasing arrangements for facsimile scanning drums and the like.

In the operation of facsimile systems employing rotating scanning drums, it is usually requisite before the start of a transmission period to phase the drums at the transmitter and receiver, even though the drums otherwise would run in perfect speed synchronism. This phasing operation is particularly important where one of the drums is comparatively heavy, or where the drum rotates at such a high speed as to have considerable inertia. This problem of phasing has been found to be particularly difficult with large or heavy drums because of the comparatively great and sudden load which is placed upon the driving mechanism at the instant of phasing. Heretofore, the phasing operation has required almost an instantaneous change from no load to full load on the driving motor and on the clutch between the motor and the drum. Since such clutches are usually of the slip-friction type, it is clear that this sudden change from no load to full load is represented by a considerable slip in the clutch with a consequent undesirable change in phase between the received phasing impulse and the actual angular phase of the drum.

Accordingly, one of the principal objects of the present invention is to provide a drive coupling between a slip-friction clutch and a scanning drum whereby the load on the clutch and the driving motor is materially reduced during phasing operations and the like.

There is one known type of phasing arrangement as illustrated for example in Patent No. 2,275,249, wherein the scanning drum is arranged to be stopped by an abutment which engages a projection on the drum or drum drive. With such an arrangement, the drum is connected at all times to the driving motor shaft either directly or through the slip-friction clutch. Consequently, there is no possibility of the drum coasting freely with respect to the motor.

Another object is to provide a drive coupling between a motor and a scanning drum which, under certain conditions, permits the drum to rotate freely and substantially independently of the usual slip-friction clutch.

A further object is to provide an improved phasing control mechanism whereby the scanning drum can coast while the clutch is stopped, and when the clutch is released it applies a positive drive to the drum, the application of which

2

positive drive can take place while the drum is coasting and which positive drive is necessary to maintain accuracy of phasing.

A feature of the invention relates to a drive coupling between a motor and a scanning drum, including a slip-friction clutch having an element which can be selectively stopped, the said element being coupled to the drum by a special one-way latch whereby, under certain conditions, the drum can coast freely with respect to the clutch, and the phasing action is effected on the stop arm and its disc which have relatively little inertia.

Another feature relates to a novel form of one-way positive drive coupling between a scanning drum and a driving motor.

A further feature relates to the novel organization, arrangement and relative interconnection of parts which cooperate to produce an improved phasing control for telegraph machines such as facsimile scanners and the like.

Other features and advantages not specifically enumerated will be apparent after a consideration of the following detailed descriptions and the appended claims.

In the drawing which represents one preferred embodiment,

Fig. 1 shows the general arrangement of the more important parts of the clutch, and the 30 drum-driving and coupling mechanism according to the invention.

Fig. 2 is an end elevation of Fig. 1, along the dotted section line, and viewed in the direction of the arrows 2—2.

Fig. 3 is an end elevation of Fig. 1, along the dotted section line, and viewed in the direction of the arrows 3—3.

Figs. 4 and 5 are enlarged detailed views of the driving and coasting control latch shown in 40 Figs. 1 to 3.

Referring to the drawing, the driving motor (not shown), is connected to the drive shaft 1, which carries at its right-hand end a slip-friction clutch 2. This clutch may be of any well-known

45 type comprising, for example, a set of three friction discs 2 and 3, which are appropriately fastened to shaft 1; and an intermediate friction disc 4 which is not connected to the shaft but is driven by frictional engagement with discs 2 and 3. A detailed description of one preferred construction for the clutch, is given in application Serial No. 501,953, filed September 11, 1943, the disclosure of which application is expressly incorporated herein by reference. Firmly at-

50 tached to member 4 is a rigid stop arm 5, which

has an inclined trailing face 6. The stopping of disc 4 is controlled by the armature 7 of an electromagnet 8, armature 7 being pivoted at its upper end (Fig. 2) in the L-shaped frame 9 on which the magnet 8 is mounted. A retractile spring 10 tends to hold the lower end of armature 7 to the left, and in the path of member 5, however, when magnet 8 is energized, armature 7 is clear of arm 5. Magnet 8 is normally continuously energized thus allowing arm 5 to rotate with shaft 1 in the direction of the arrow (Fig. 2).

Arm 5 when released, is adapted to engage the left-hand end of a latch 11 which is pivotally mounted on a pin 12 in a slotted guide or stud 13 which is rigidly fastened to the drum driving plate 14. The slot 15 in member 13 is inclined to correspond with the inclined right-hand end of latch 11 so that when these inclined surfaces are in contact as shown in Fig. 4, the latch 11 extends perpendicularly to plate 14. A spring 16 has one end attached to latch 11 and the other end to member 13, and it is coiled or biased so that it normally holds latch 11 in the position shown in Fig. 4.

Plate 14 is fastened to the drum shaft 17 which is journaled at opposite ends in suitable ball bearings 18 and 19. An end thrust ball bearing 20 is located between the recessed right-hand end of shaft 17 and the bearing plate 21, the proper bearing pressure being obtained by a spring 22 located between bearing plate 23 and a collar 24 fastened to shaft 17. This arrangement provides a frictionless thrust bearing which prevents any lengthwise vibration or oscillation of the drum as it is rotating. The shaft 17 carries the usual lead screw 25 and its right-hand end is slotted at 26 and is slidably keyed to scanning drum 27, so that as shaft 17 turns, the drum 27 also turns and advances along the shaft, depending upon the pitch of the lead screw thread. For a detailed description of a preferred drum and lead screw arrangement, reference may be had to U. S. Patent No. 2,138,784, the disclosure of which is expressly incorporated herein by reference.

With the arrangement as described, the drum 27 can continue to rotate freely, even though the disc 4 and the arm 5 are held stationary by armature 7 during the phasing operation. This is so, because when the drum, as a result of its inertia, continues rotating, the latch 11 at its left-hand end (Fig. 5), strikes the arm 5 which is now stationary, with the result that latch 11 freely pivots around pin 12 without stopping the drum. If a phasing impulse is not received to energize magnet 8 during the interval required for the drum to make one complete revolution, the drum continues to rotate by reason of its inertia. The friction of the drum mounting is sufficiently low so that the drum will coast as many as four or five revolutions before coming to rest. Should the phasing impulse be received while the drum is coasting, armature 7 is attracted by magnet 8 and releases arm 5 for rotation with shaft 1. Arm 5 thereupon gradually catches up on the coasting latch 11 because of the gradual deceleration of the drum, until the latch actually engages arm 5 as shown in Fig. 4. In this relation, the driving force of arm 5 positively rotates latch 11 counter-clockwise around pin 12 (Fig. 4) to cause a positive driving connection between shaft 1 and shaft 17. However, the load upon the clutch and motor at this initial contact is very much less than it would be

if member 5 were required to start the drum from a standstill position. For example, if the drum is coasting at half its normal speed, the load on the clutch is only one-quarter of that required to accelerate it to the same speed as would be the case if the members 3 and 8 were always positively connected. It should be observed that when the latch 11 is positively driving plate 14, the frictional load of the drum and its bearings is sufficient to provide back pressure against the member 5 so that the latch 11 is held against the said member 5 and thereby continues to drive the drum positively.

While one particular embodiment of the invention has been disclosed herein, it will be understood that various changes and modifications may be made without departing from the spirit and scope of the invention.

What I claim is:

20 1. A phasing arrangement for a telegraph apparatus such as a facsimile scanning drum comprising, a continuously running driving member for said drum, a driving connection between said member and said drum, said connection including a device which can be stopped to allow the drum to continuously coast with relation to said driving member while said device is stopped, said device when released allowing the driving member to impart positive driving force to the drum.

25 2. A phasing arrangement for a telegraph apparatus such as a facsimile scanning drum comprising, a continuously running driving member, a scanning drum having substantial rotational inertia, a driving connection between said member and said drum including a stopping device and a one-way positive-latch coupling between said driving member and said drum to allow said drum to continually coast with relation to said driving member while said device is operated.

30 3. A phasing arrangement for a telegraph device such as a facsimile scanning drum, comprising a continuously running driving shaft, a driven shaft for the drum, said drum having considerable rotational inertia and connected to said driven shaft, a slip-friction clutch between said two shafts having a member frictionally driven from said driving shaft, and a one-way latch device between said member and said driven shaft for imparting a positive drive to said driven shaft but without permanent connection to said driving shaft, while allowing the driven shaft to coast continuously even when said member is stationary.

35 4. A phasing arrangement for a telegraph device such as a facsimile scanning drum, comprising a continuously running driving shaft, a driven shaft for the drum, a member frictionally driven from said driven shaft and drum, stopping means for said member to cause said member to be stopped without stopping said driven shaft and to allow said driven shaft to coast freely and continuously even while the said member is stopped.

40 5. A phasing arrangement for a telegraph device such as a facsimile scanning drum, comprising a driving shaft, a driven shaft, a facsimile scanning drum connected to said driven shaft, a slip-friction clutch having a member which can be stopped without stopping said driving shaft, a device connected to said driven shaft and having a pivoted arm adapted to be engaged by said member to impart positive driving force to the driven shaft, said arm allowing said driven shaft and drum to coast freely and continuously with respect to said driving shaft while said member is stopped.

6. A phasing arrangement for a telegraph device such as a facsimile scanning drum, comprising a continuously running driving shaft, a driven shaft for said drum, a slip-friction clutch having a member frictionally coupled to the driving shaft, a stop arm carried by said member, an electromagnet having means to engage said member to stop it without stopping said driving shaft, a driving plate fastened to the driven shaft, and a pivoted latch member extending from said plate into the path of rotation of said stop arm.

7. An arrangement according to claim 6 in which said pivoted latch member is pivotally mounted in a slotted guide extending perpendicular to said driving plate, said latch being normally spring-pressed so as to form an effective elongation of said guide.

8. A phasing arrangement for a telegraph device such as a facsimile scanning drum, comprising a continuously running driving source for said drum, means to drive the drum from said

5

10

15

20

source preliminarily to the receipt of a phasing signal, means to disconnect the drum from said driving source while allowing the drum to coast freely, and means responsive to the receipt of a phasing signal to control the connection of said driving source to said drum while the latter is coasting in the same direction as that of said driving source.
